United States Patent

Des. 239,971
Patented May 18, 1976

239,971

CLOCK RADIO

Leonard Kaye, Westfield, N.J., assignor to
Capehart Corporation, New York, N.Y.

Filed Nov. 14, 1974, Ser. No. 523,840

Term of patent 14 years

Int. Cl. D10—01; D14—03

U.S. Cl. D56—4 B

FIG. 1

FIG. 2

FIG. 3

FIG. 5

FIG. 4

FIG. 6

FIG. 1 is a front, top and right side perspective view of a clock radio showing my new design;

FIG. 2 is a front elevational view;

FIG. 3 is a left side elevational view;

FIG. 4 is a right side elevational view;

FIG. 5 is a top plan view; and

FIG. 6 is a bottom plan view.

The rear of the clock radio is plain and unornamented.

I claim:

The ornamental design for a clock radio, as shown and described.
